UNITED STATES PATENT OFFICE.

FREDERICK SEABERG, OF CHICAGO, ILLINOIS, ASSIGNOR TO NATIONAL DUMP CAR COMPANY, OF CHICAGO, ILLINOIS, A CORPORATION OF MAINE.

DOOR-OPERATING MECHANISM FOR RAILWAY-CARS.

1,151,407.

Specification of Letters Patent.

Patented Aug. 24, 1915.

Application filed February 17, 1911. Serial No. 609,198.

To all whom it may concern:

Be it known that I, FREDERICK SEABERG, a citizen of the United States, and resident of Chicago, in the county of Cook and State 5 of Illinois, have invented certain new and useful Improvements in Door-Operating Mechanism for Railway-Cars, of which the following is a description, reference being had to the accompanying drawings, which 10 form a part of my specification.

My invention relates to mechanism for operating the dumping doors of a car, being more especially adapted for use in connection with the hopper-bottom type of cars, 15 wherein the doors form a part of the hopper, and open through the action of gravity.

The object of my invention is to provide a simple and efficient mechanism that will simultaneously operate the doors to both 20 sides of the longitudinal center of the car, and which will at the same time automatically lock the doors when they are brought to a closed position, as will more fully appear from the following detailed description 25 of the accompanying drawings, wherein:—

Figure 1 is a side elevation of a portion of a dump car provided with my improved door operating mechanism; the doors being shown closed. Fig. 2 is a cross sectional 30 view taken on the line 2—2 of Fig. 1. Fig. 3 is a sectional view taken on line 3—3 of Fig. 2 looking downward. Fig. 4 is a vertical sectional view taken on the line 4—4 of Fig. 2 looking in the direction of the arrows.

I have shown my invention in Fig. 1 applied to that class of dump cars which are provided with a dumping hopper-bottom arranged longitudinally of the car, of which

I have shown my invention in Fig. 1 applied to that class of dump cars which are provided with a dumping hopper-bottom arranged longitudinally of the car, of which the dumping doors form a part; the doors when closed forming a V-shape hopper-bottom in cross section. The doors extend longitudinally of the car between the trucks and constitute what may be termed two swinging dumping sections 5 and 6 at opposite sides of the longitudinal center line 45 of the car; one or more doors being arranged on the same side of the longitudinal center line.

The doors 5 and 6 are suitably pivoted at the points 7 to the frame or longitudinal 50 sills of the car in a well known manner.

Yieldingly mounted or secured to the door 6, by the plate 8, see Fig. 2, is a shaft 9, which extends longitudinally beneath the door or doors to the other end of the dumping section, at which point it is provided, if 60 desired, with mechanism substantially similar to that now to be described.

The shaft 9 is provided at its end or ends with the link or arm 10, which is secured to the shaft against rotation thereon. 65

Pivotedly secured to the outer end of the link or arm 10 is a connecting link or bar 11. This link or bar 11 is also secured to the shaft 12. This shaft 12 extends longitudinally beneath the door 5, located at the opposite side of the longitudinal center line of 70 the car.

The doors 5 and 6 bear or rest on the shafts 9 and 12 and are held in place thereby.

The plate 8 is provided with a slot as 75 shown in Fig. 2, so that shaft 9 may have slight lateral movement transversely of the door, during the operation thereof.

Connecting link or bar 11 is preferably composed of the two members 11^a and 11^b, 80 see Fig. 3, arranged on opposite sides of the link or arm 10; and these members 11^a and 11^b, by reason of their relation to the shafts and arm 10, and the manner in which they are secured in place, are bent or bowed 85 at a point intermediate of their ends, so as to permit the axes of the respective pivotal points—namely, the point of connection between arm 10 and link-members 11^a, 11^b and shafts 9 and 12—to occupy substantially the 90 same horizontal plane, as clearly shown in Fig. 2.

The link or arm 10 is so secured to the shaft 9, that it will extend out in a substantially horizontal direction when the doors 95 are either completely closed or opened. By having the link or arm 10 pivoted between the bifurcations of link or bar 11, or its separate members 11^a or 11^b, as shown in the drawings, and having the link or bar 11 100 take over the shaft 9, as shown, it is apparent that the end of link or bar 11 cannot drop appreciably below the horizontal plane or "dead center" of the pivotal points between the links and shafts. With the construction wherein the pivotal point between arm 10 and link 11 are as shown and described, the operation of the mechanism is made very easy, and the dropping of the pivotal point, between links 10 and 11, below 110

the "dead center," would necessitate the exertion of greater force to lift the arms above the "dead center." It is apparent, however, that even if said point should be somewhat below the horizontal plane, it is still possible to operate the mechanism.

With the links in the position shown in full lines in Fig. 2, that is, with their ends in the same horizontal plane, or at a "dead center" as it were, the doors will be securely locked in closed position.

Extending transversely of the car, is a rotatable shaft 13, whose outer ends may be formed to receive any suitable operating device. This rotatable shaft 13 may either be mounted at an intermediate point in the car, as shown in Fig. 1, between the dumping sections on the same side of the longitudinal center line of the car, or it may be mounted at either end of the dumping sections, if desired. Secured to this shaft 13 and adapted to be wound about it, is the flexible connection or chain 14, one end of which is also secured to the link or arm 10. I have illustrated the connection between the flexible connection or chain 14, and the link or arm 10, in the shape of the long link 15. This link 15 is preferably made to take to both sides of arm 10 and be pivotally secured thereto, while the outer end thereof is preferably bent, as illustrated in Fig. 2, thereby providing means for maintaining the flexible connection 14 in proper relation with the ends or pivotal connection between arm 10 and bar 11.

An arm 16, which may either be a separate member or formed integral with arm 10, extends from shaft 9 in the opposite direction to arm 10. This arm 16 is connected with shaft 13 by the flexible connection or chain 17; the chain 17 is secured to the shaft 13 and arranged to wind thereon in the reverse direction to the winding of the flexible connection or chain 14. Chain 17 is brought up between the two members of link 11 as clearly shown in Fig. 3, and is therefore constantly maintained in proper position during the operation of the doors.

It is apparent from the construction shown and described that when it is desired to open the doors, shaft 13 must be rotated in a direction which would tend to wind up chain 14, thereby slackening or unwinding chain 17; this operation will compel the chain 14 to pull up against the ends or pivotal connection between arm 10 and bar 11, thereby forcing the pivotally connected ends of bars 10 and 11 up above the horizontal plane or "dead center," in which the pivoted ends are shown in full lines in Fig. 2. The moment this has been accomplished, the weight of the doors and the load will complete the further movement of the mechanism to allow the further opening of the doors. When the doors are fully opened, the

position of the operating mechanism will be as shown by dotted lines in Fig. 2; the free ends of the doors resting against the shafts 9 and 12.

When it is desired to bring the doors to a closed position and the operating mechanism into a locking position, the shaft 13 is rotated in an opposite direction to that in which it was rotated to release the mechanism, so as to wind up the chain 17, and unwind chain 14. The winding up of chain 17,—the one end of which is secured to the end of arm 16 which has now been moved to a position away from the longitudinal center line of the car as shown in dotted lines, Fig. 2,—will immediately apply pressure on the pivotal point between arm 10 and bar 11, which point, when the doors are open, will be intermediate of the shafts 9 and 12, as clearly shown in dotted lines, Fig. 2. The upward pressure of the chain 17 on this pivotal point will immediately throw the connection upward and draw arm 16 downward and around from the position shown in dotted lines; the continued rotation of shaft 13 swinging arms 10 and 16 about shaft 9 so as to move the point of connection between arms 10 and members 11^a and 11^b away from a position between shafts 9 and 12; and this movement compels the shafts 9 and 12 to ride upward on their respective brackets or tracks, thereby bringing the mechanism back to the normal or locking position shown by the full lines in Fig. 2.

When desired, the sloping brackets or tracks 18 and 19, of the construction shown in Fig. 2, may be employed, so that the weight of the doors and the load thereon may be transmitted through shafts 9 and 12 to the tracks or brackets 18 and 19.

The nature of my door operating mechanism is such, that after the doors have been brought to a closed position, with the respective pivotal points between the arm, bar and shafts, thrown into substantially the same horizontal plane, as clearly shown in Fig. 2, the mechanism will lock the shafts 9 and 12 in the positions adjacent to the longitudinal center line of the car, and the shafts in turn will hold the doors in place independently of the operating shaft 13 and chains 14 and 17, so that any slack in the chains will not release the doors, the latter being firmly secured in place until an upward pull has been applied to the proper chain, namely chain 14.

I have shown and described what I believe to be the simplest construction or form of my invention, but the same may be varied in certain details without departing from the spirit of my invention, and I do not wish to be understood as limiting myself to the exact construction shown and described, but

What I claim and wish to secure by Letters Patent is:—

1. Operating mechanism for the doors of a hopper car which are arranged to swing toward and away from each other, to close and open respectively, comprising a rotatable shaft, means having a controlling relation with the doors at opposite sides of the longitudinal center line of the car, said means being provided with a yielding point intermediate of its ends adapted to move from a point intermediate of the free ends of the doors to a point at one side of the point of connection with one of the doors, whereby the position of the doors is controlled, and flexible connections between the shaft and said means and so related to the yielding point in said means that the rotation of said shaft in one direction will move 10 said point to open the doors while the rotation in the opposite direction will move the point to close the doors.
2. Operating mechanism for the doors of a hopper car, the doors being hinged at their outer sides so as to swing toward each other when they are moved to closed position, comprising a rotatable shaft, means having operative relation with oppositely disposed doors, extending in a transverse direction, and provided with an intermediate pivotal point, and flexible means intermediate of the shaft and said first mentioned means and so related thereto that the rotation of the shaft in different directions will move the 20 intermediate pivotal point of said first mentioned means toward or away from the longitudinal center line of the car to either open or close the doors respectively.
3. Operating mechanism for the doors of a hopper car, wherein the free ends of the doors abut against each other when the doors are in closed position, comprising a rotatable shaft, means having operative relation with the oppositely disposed doors and provided with an intermediate pivotal point, and a pair of members intermediate of the shaft and said means, said members being adapted to extend about the shaft in opposite directions, the members being so 30 connected to said means that one member will control the pivotal point of the means when the doors are closed, while the other member will control the pivotal point of said means when the doors are opened.
4. Operating mechanism for the doors of a hopper car arranged to swing toward and away from each other to close or open respectively, comprising pivotally mounted members having operative relation with the doors on opposite sides of the longitudinal center line of the car, said members being pivotally connected together and so arranged that the point of connection between said members will be moved in a direction 40 toward or away from the longitudinal cen-

ter line of the car and control the doors, and flexible means extending about the pivotal connection between said members and secured to one of said members and to the shaft so that the rotation of the shaft in one direction will move the pivotal connection of the members in one direction to open the doors, while rotation in the opposite direction of the shaft will close the doors and lock them in position.

75

5. Operating mechanism for the hopper doors of a dump car wherein the doors are hinged at their outer sides so as to swing toward each other when moved to closed position, comprising means whereby oppositely disposed doors are simultaneously controlled, a portion of said means extending lengthwise beneath the doors to support the same, while the other portion extends transversely of the doors and controls the 80 position of the first mentioned portion, a rotatable shaft operable from either side of the car, and positive flexible connections between the shaft and the last mentioned portion of said means whereby said portion is operated so as to move the first mentioned portion of the means toward or away from the longitudinal center line of the car to open or close the doors respectively.

80

6. Operating mechanism for the hopper doors of a dump car whose free ends abut against each other when the doors are closed, comprising means pivotally mounted beneath the doors and in operative relation with the doors at opposite sides of the longitudinal center line of the car, said means being provided with an intermediate yielding point arranged to move transversely of the car, and mechanism having positive relation with said means and adapted to apply pressure to said intermediate yielding point to move said means into locking or 90 unlocking positions.

95

7. Operating mechanism for the downwardly swinging doors of a hopper car, wherein the doors are arranged to swing toward each other when moved to closed position, comprising a member rotatively mounted beneath each door, the members of oppositely disposed doors being connected together and so arranged that the point of connection between said members may be moved to either side of one of the members beneath the doors, and means connected to one of said members so as to apply pressure 100 to the pivotal connection between the members whether the members are in locking or unlocking position.

105

8. Operating mechanism for the hopper doors of a dump car, comprising means extending transversely of the car whereby oppositely disposed doors are controllably connected together and locked in closed position, a rotatable shaft, and a pair of flexible members connected with said shaft 110

115

120

125

130

- and said means and adapted to move said means in a direction transversely of the car when the shaft is rotated in either direction.
9. Operating mechanism for the hopper doors of a dump car comprising means having operative relation with the doors located at opposite sides of the longitudinal center line of the car, said means being provided with an intermediate yielding point, a rotatable member fixedly mounted, and a pair of members secured to said rotatable member and to said means, the relation between said pair of members and the means being such that one member will affect the intermediate yielding point of the means when the latter is in locking position, while the other member will affect said yielding point when the means is in an unlocking position.
10. Operating mechanism for the gravity opening doors of a dump car, comprising an operating shaft extending transversely of the car, means extending transversely of the car and having controlling relation with the doors on opposite sides of the longitudinal center line of the car, said means being provided with an intermediate yielding point which is adapted to be moved toward or away from the longitudinal center line of the car, and a pair of flexible members secured to said shaft so as to extend about the shaft in opposite directions when the latter is rotated, said members being also connected to said means so that the one member will extend about said intermediate yielding point when the means is moved into locking position, while the other member will extend about said intermediate yielding point when said means is moved into unlocking position.
11. Operating mechanism for the gravity opening doors of a dump car, comprising an operating shaft, a pair of members, pivotally connected together and extending transversely of the car, having operative relation with the doors at opposite sides of the longitudinal center line of the car, and a pair of flexible members adapted to extend about said operating shaft in opposite directions when the latter is rotated, said flexible members being also secured to one of the transversely extending members so as to engage with the pivotal connection between the transversely extending members whether the latter are in locking or unlocking positions.
12. Operating mechanism for the oppositely swinging doors of a hopper car, comprising a pair of links having operative relation with the doors on opposite sides of the longitudinal center line of the car, said links being pivotally connected together so as to permit the pivotal point to move to a point intermediate of the doors when the latter are opened and intermediate of the car-side and the adjacent door when the doors are closed, and means connected to the car frame and to one of said links so as to force the pivotal connection between the links and move the links into locking or unlocking positions.
13. Operating mechanism for the hopper doors of a dump car comprising means whereby the oppositely disposed doors are simultaneously controlled, said means being provided with an intermediate yielding connection adapted to move through a curvilinear path to a point intermediate of the doors when the latter are opened and between the car-side and one of the adjacent doors when the latter are closed, a rotatable shaft, and a pair of flexible connections between the shaft and said means adapted to force said intermediate yielding connection toward or away from the longitudinal center line of the car and thereby unlock or lock the doors.
14. Operating mechanism for the downwardly opening doors of a car arranged to swing toward and away from each other, to close and open respectively, comprising a pair of members oscillatingly mounted, having controlling relation with oppositely disposed doors, said members being yieldingly connected together so that said connection may be swung toward or away from the longitudinal center line of the car, a rotatable shaft, and a pair of flexible members between the shaft and one of said first mentioned members, adapted to extend about the shaft in opposite directions when the shaft is rotated, said flexible members being so connected with said first mentioned member that one of the flexible members will have controlling relation with the yielding connection between the first mentioned members when the latter are in locking position, while the other flexible member will have controlling relation with said yielding connection when the first mentioned members are in unlocking position.
15. Operating mechanism for the downwardly opening oppositely disposed doors of a car arranged to swing toward and away from each other, to close and open respectively, comprising transversely extending means oscillatingly mounted adjacent to and in contact with the free ends of said oppositely disposed doors, said means being provided with an intermediate pivotal connection, a rotatable shaft, and a pair of flexible members adapted to extend about the shaft in opposite directions when the latter is rotated and also connected with a portion of said means at opposite sides of the point where said means contacts with the free end of one of the doors, whereby the means may be moved into locking and unlocking positions.
16. Mechanism for operating downwardly opening oppositely disposed doors of a

- dump car, said doors being adapted to swing toward and away from each other to close and open respectively, comprising means having movement transversely of the doors 5 during operation of said mechanism and adapted to support the doors, transversely disposed means provided with an intermediate yielding point and connected with said first mentioned means, the relation between 10 both means being such that said intermediate yielding point and points of connection will occupy substantially the same horizontal plane when the doors are closed thereby automatically locking the doors independently 15 of other portions of said mechanism, and means operable from either side of the car and arranged to move said second-mentioned means into locking and unlocking positions.
- 20 17. A dump car having an unobstructed center discharge opening, oppositely swinging doors hinged at the outer sides of the opening, means having operative relation with the oppositely disposed doors for supporting them in closed position and automatically lock the same when moved to one position, means located beneath and supporting the first mentioned means, means for simultaneously displacing the first mentioned means to permit the doors to open, said displacing means being adapted to move about a fixed axis operable from either side of the car.
18. A dump car having an unobstructed center discharge opening, oppositely swinging doors hinged at the outer sides of the opening, shafts beneath the doors, supports for said shafts secured to the under frame 35 of the car, said shafts being moved toward 40 and away from each other to close and open the doors respectively, connections between the shafts whereby both shafts are simultaneously operated and the doors and shafts locked in closed position independently of 45 the other portions of said mechanism, and means for operating the connections between the shafts, said means being adapted to move about a fixed axis operable from either side of the car.
- 50 19. A dump car having an unobstructed center discharge opening, oppositely swinging doors hinged at the outer sides of the opening, shafts beneath the doors for supporting them in closed position, and being 55 displaceable from their supporting position to permit the doors to open, one of said
- shafts being connected to one of the doors so as to have movement of rotation in relation to the door, connections between said rotating shaft and the shaft beneath the opposite door, means for operating the rotating shaft, said operating means extending to each side of the car.
20. Operating mechanism for the doors of a dump car having an unobstructed center 60 discharge opening in which the oppositely swinging doors are hinged at the outer sides of the opening, comprising means located beneath the doors and having controlling relation with the oppositely disposed doors 65 whereby the latter are supported and locked in closed position, and means having a fixed rotative relation with and extending transversely of the car so as to be operable from both sides of the car whereby said first mentioned means is moved out of and into said supporting position.
21. Operating mechanism for the hopper doors of a dump car which are adapted to swing toward and away from each other to 70 close and open respectively, comprising means adapted to support the oppositely disposed doors, said means being provided with an intermediate yielding point whereby the doors will be locked in closed position when 75 said means is moved into one position, means secured to the frame of the car and providing a track-way for said first mentioned means whereby the latter is held in proper relation with said doors, and means extending 80 transversely of the car operable from either side of the car and arranged to move the first mentioned means into locking and unlocking positions.
22. Operating mechanism for the down- 90 wardly opening doors of a dump car having an unobstructed discharge opening, the doors being hinged at the outer sides of the opening, comprising means located beneath oppositely disposed doors and rotatably se- 95 cured to one of the doors whereby both doors are supported and locked in closed position, means whereby said first mentioned means is guided during the operation of the doors, and means operable from both sides of the 100 car whereby the first mentioned means is moved into or out of locking position.
